UNITED STATES PATENT OFFICE.

OLIVER J. JOHNSON, OF WHEELING, WEST VIRGINIA.

CAN-BODY-MAKING MACHINE.

971,278.

Specification of Letters Patent. Patented Sept. 27, 1910.

Application filed May 21, 1907. Serial No. 374,910.

To all whom it may concern:

Be it known that I, OLIVER J. JOHNSON, a citizen of the United States, residing at Wheeling, in the county of Ohio and State of West Virginia, have invented a new and useful Improvement in Can-Body-Making Machines, of which the following is a specification.

This invention relates more particularly to improvements in that type of machine for making can bodies exemplified in U. S. Letters Patent No. 783,788, granted to me February 28, 1905, in which the sheet metal blanks are carried successively first to the mechanism which forms the seam hooks on the opposite edges of the blank, and then to a mechanism, arranged in advance of the hook forming mechanism in the line of feed of the blanks, which shapes the blank around a horn or form, and interlocks the hooks and completes the joint. The improvements are not, however, as will be apparent from this specification, restricted in application to this particular type of machine. In machines of the sort mentioned as ordinarily operated the blanks are fed one at a time to an intermittently operating carrier and at each forward movement the carrier delivers one blank to the hook-forming mechanism and another to the body-forming mechanism, so that one blank is operated upon in each mechanism at the same time and one body is completed at each operation of the machine, or for each forward movement of the carrier.

The primary object of this invention is to greatly increase the output of can body making machines, without materially adding to the cost of manufacture and operation thereof, by adapting the machine for completing a plurality of can bodies simultaneously instead of one at a time. A number of blanks must be fed to the machine for each operation equal to the number of bodies completed at one operation and this cannot be done manually by one operative unless the machine is run so slowly as to defeat the object of the invention. This object is attained in the machine herein described by making each of the mechanisms large enough to operate upon two blanks simultaneously and providing automatic mechanism for feeding two blanks at a time to the carrier, one in advance of the other, or in tandem, whereby at each forward movement of the carrier two blanks are delivered

to the hook-forming mechanism and two other blanks to the body-forming mechanism. Thus the output of the machine is doubled when operated at substantially the usual speed.

In the accompanying drawings, consisting of two sheets: Figure 1 is a fragmentary longitudinal sectional elevation of a can body machine embodying the invention. Fig. 2 is a plan view, partly in section, thereof. Fig. 3 is a transverse sectional elevation thereof, in line 3—3, Fig. 1.

Like letters of reference refer to like parts in the several figures.

A represents the hook-forming mechanism and B the body forming and the lock seam finishing mechanism of a can body making machine. The particular construction of these mechanisms forms no part of this invention and it is sufficient for a complete understanding of this invention to say that they are arranged in tandem, or one in advance of the other, as regards the direction of movement of the blanks through the machine, and that they can be constructed as described in my said patent, or like any of the many well known mechanisms employed for the purpose, except that each mechanism is made long enough in the direction of movement of the blanks to operate at the same time upon two blanks disposed one in advance of the other.

C represents the intermittently moving carrier to which the blanks are fed, as hereinafter described, and which carries them to the hook and body-forming mechanisms. A horizontally reciprocating carrier is shown consisting of connected side bars having pivoted dogs c for engaging the opposite sides of the blanks, and a central pivoted toothed push bar c' extending forwardly ahead of the side bars into the horn of the body-forming mechanism for shoving the blanks from the hook forming mechanism A into the body forming mechanism B and out of the latter. The carrier is reciprocated in guide-ways on a suitable bracket or part c² of the machine frame by a rock shaft D having a rock arm d connected by a link d' to the carrier. The shaft D is rocked by suitable means not shown.

The blanks X are placed over the carrier C in a suitable holder E from which they are fed two at a time onto the carrier, one in advance of the other and each in front of a pair of carrier dogs. The blank holder

shown consists of opposite parallel supporting bars or plates e having oppositely inclined bottom portions on which the blanks rest and vertical side walls between which the blanks are held from lateral displacement. The bars e are laterally adjustable, to accommodate and properly center blanks of different widths, on cross rods e' connecting side uprights e^2 rising from the frame bracket e^2 . The blanks are preferably stood on edge in the holder in two stacks with the side edges of the first blanks of the stacks resting against retaining fingers or lips f extending inwardly from the side walls of the holder bars e at the front and rear ends of the holder.

One blank is taken from each stack at the same time and the two deposited simultaneously on the reciprocating carrier by suitable feed devices G and G' . In the mechanism shown, these feed devices consist of vacuum cups attached to the lower ends of swinging feed arms g g' arranged one in front of one stack of blanks and the other in rear of the other stack. The arms depend from horizontal shafts g^2 journaled in the uprights e^2 and are operated by arms g^3 on said shafts connected by links g^4 to an arm g^5 on a horizontal rock shaft g^6 which is journaled in a bearing on the frame bracket e^2 and has another arm g^7 connected in turn by a link g^8 to an arm g^9 on the rock shaft D which operates the reciprocating carrier. The feed cups are connected to means (not shown) of ordinary or suitable construction whereby the air is exhausted from them when they are pressed against the blanks, so that when the feed devices are moved away from the stacks the two first blanks will adhere to the feed devices and be pulled thereby from between the retaining fingers of the blank holder.

H H' represent two blank chutes, arranged opposite to the opposite ends of the holder, to which the feed devices carry the blanks, and which direct the blanks downwardly onto the reciprocating carrier. The chutes preferably incline downwardly toward each other and consist of parallel spaced side and intermediate rails attached at their upper ends to yokes or frames h which are adjustably secured to the uprights e^2 . The chutes are suitably shaped to deposit the blanks gently on the carrier in proper position in front of adjacent pairs of the feed dogs. I represents two swinging stops arranged between the lower ends of the chutes near the opposite sides of the carrier, for preventing the blanks from sliding past the proper position on the carrier. These stops are normally held in a central position by suitable light springs i , and can yield to allow the forward movement of the rear blank beneath them with the carrier. The stops are more especially for preventing the rear blank, which slides

down the chute H in a forward direction, from riding over the inclined rear edges of the carrier feed dogs onto the front blank.

The operation of the machine is as follows: The feed devices are swung toward and pressed against the first blanks of the stacks during the forward movement of the reciprocating carrier and these blanks cling to the feed devices and are pulled from the holder in the return swing of the feed devices during the rearward movement of the carrier. As the feed devices swing between the rails of the chutes the blanks are arrested by striking such rails and are stripped from the feed devices and slide down the chutes onto the carrier in front of adjacent pairs of the feed dogs thereof in time to be moved forward with the carrier at its next forward movement. Two blanks are thus fed to the carrier simultaneously prior to each forward movement thereof, and the travel of the carrier is sufficient to move the two blanks into proper position in the hook forming mechanism and carry the preceding two blanks on the carrier from the hook forming mechanism into proper position in the body forming mechanism. Two blanks are operated upon by the hook-forming mechanism and two others by the body-forming mechanism simultaneously prior to each forward movement of the carrier so that two bodies are completed for each reciprocation of the carrier.

The mechanism described feeds the blanks together to the carrier in tandem as regards the direction of movement of the blanks into the machine by the carrier. Only one hook-forming mechanism and one body-forming mechanism is employed and only one carrier for moving the blanks to and from these mechanisms. The machine, therefore, has no more parts, excepting the duplication of the feeding devices, than a machine for making one body at a time, it being only necessary to lengthen the hook and body-forming mechanisms and the stroke of the carrier.

The invention is not restricted to the particular mechanisms employed for operating upon the blanks, nor to the construction of the feeding mechanism, as other means could be employed for simultaneously feeding two blanks in tandem, or one in advance of the other, to the mechanism for operating upon them.

I claim as my invention:

1. In a can-body making machine, the combination of a movable conveyer for the body blanks, mechanism for feeding a plurality of blanks to said conveyer one in advance of the other with respect to the direction of movement of said conveyer, and means for operating said conveyer to carry the blanks together to a body-forming mechanism, which is of sufficient length in the di-

rection of movement of said conveyer to operate simultaneously on the plurality of blanks, and to carry the blanks together away from said mechanism, substantially as set forth.

2. In a can-body making machine, the combination of a movable conveyer for the body blanks, mechanism for feeding a plurality of blanks to said conveyer one in advance of the other with respect to the direction of movement of said conveyer, and means for operating said conveyer to carry the blanks together to one after another of mechanisms which perform successive operations on the blanks and which are arranged in relatively fixed position one in advance of the other with respect to the direction of movement of the conveyer and each of which is of sufficient length in the direction of movement of said conveyer to operate simultaneously on the plurality of blanks, substantially as set forth.

3. In a can-body making machine, the combination of a movable conveyer for the body blanks, mechanism for feeding a plurality of blanks to said conveyer one in advance of the other with respect to the direction of movement of said conveyer, and means for operating said conveyer to carry the blanks simultaneously first to an edging mechanism and then to a body-forming mechanism, which mechanisms are arranged in relatively fixed position one in advance of the other with respect to the direction of movement of said conveyer and each of which is of sufficient length in the direction of movement of said conveyer to operate simultaneously on the plurality of blanks, substantially as set forth.

4. The combination of a movable conveyer for the blanks, a holder above said conveyer in which the blanks stand in planes transversely to the plane of movement of said conveyer, and means for feeding two blanks at the same time one from each end of said holder onto said conveyer, one in advance of the other, substantially as set forth.

5. The combination of a conveyer for flat blanks, means for holding the blanks in two stacks above said conveyer one in advance of

the other relative to the direction of movement of said conveyer with the blanks standing on edge in planes transverse to the direction of movement of said conveyer, and means for feeding two blanks at the same time one from each stack downwardly toward each other onto said conveyer one in advance of the other, substantially as set forth.

6. The combination of a movable conveyer for the blanks, a holder above said conveyer in which the blanks stand on edge in planes transverse to the plane of movement of said conveyer, feed devices at opposite ends of said holder for taking the blanks therefrom, and means for operating said feed devices to feed two blanks from said holder in opposite directions toward each other onto said conveyer one in advance of the other, substantially as set forth.

7. The combination of a carrier for the blanks, a holder above said carrier in which the blanks are held transversely relative to the direction of movement of the carrier, feed devices at opposite ends of said holder for taking two blanks therefrom, and oppositely inclined chutes to which the feed devices deliver the blanks and which direct the blanks downwardly onto the carrier one in advance of the other, substantially as set forth.

8. The combination of a movable conveyer for the blanks, a holder above said conveyer in which the blanks stand on edge in planes transverse to the plane of movement of said conveyer, feed devices at opposite ends of said holder for taking the blanks therefrom, means for operating said feed devices to feed two blanks from said holder in opposite directions toward each other onto said conveyer one in advance of the other, and a device for preventing one blank from overlapping the other on said conveyer, substantially as set forth.

Witness my hand this 15th day of May, 1907.
